United States Patent Office

Des. 183,544
Patented Sept. 16, 1958

183,544

TRICYCLE FRAME

Viktor Schreckengost, Cleveland Heights, Ohio, assignor
to The Murray Ohio Manufacturing Company, Cleve-
land, Ohio, a corporation of Ohio

Application February 25, 1957, Serial No. 44,981

Term of patent 14 years

Cl. D34—15

Fig. 1

Fig. 2

Fig. 3

Figure 1 is a side elevational view of a tricycle frame, showing my new design, the opposite side being a mirror image thereof;

Figure 2 is a top plan view; and

Figure 3 is a rear elevational view thereof.

I claim:

The ornamental design for a tricycle frame, substan-
tially as shown and described.
